UNITED STATES PATENT OFFICE.

DAVID LANE FRY, OF LEBANON, OREGON.

DESIGN FOR A WATCH-CHAIN.

SPECIFICATION forming part of Design No. 21,689, dated July 5, 1892.

Application filed June 11, 1892. Serial No. 436,388. Term of patent 3½ years.

To all whom it may concern:

Be it known that I, DAVID LANE FRY, a citizen of the United States, residing at Lebanon, in the county of Linn and State of Oregon, have invented a new and useful Watch-Chain, of which the following is a specification.

The invention relates to a new and original design for watch-chains.

The object of the present invention is to provide an ornamental and attractive watch-chain; and the essential feature resides in a watch-chain provided with link-bars having the configuration of type and provided with a charm having the configuration of a quad.

The figure of the drawing represents a perspective view of a watch-chain, showing the new and original design.

Referring to the drawing, 1 designates a watch-chain provided with a series of link-bars 2, connected by plain links 3 and having the configuration of type. The chain is pro-

vided at one end with a snap-ring 4 and at the other end with a bar 5, which is connected with the adjacent link-bar 2 by a short chain or series of links. The link-bars are provided at their ends with perforations, in which are arranged the connecting-links 3. A charm 6 of the shape of a quad is connected with the watch-chain by a short chain 7.

What I claim is—

The design for a watch-chain herein shown and described, the same comprising the type-shaped link-bars and the quad-shaped charm, as set forth.

In testimony that I claim the foregoing as my own I have hereto affixed my signature in the presence of two witnesses.

DAVID LANE FRY.
